UNITED STATES PATENT OFFICE.

WILLIAM D. FORSYTH, OF YOUNGSTOWN, OHIO, ASSIGNOR TO RAILWAY PRODUCTS CORPORATION, OF BUFFALO, NEW YORK, A CORPORATION OF NEW YORK.

CAR-TRUCK SIDE FRAME.

1,125,299.

Specification of Letters Patent. Patented Jan. 19, 1915.

Application filed June 1, 1914. Serial No. 842,156.

To all whom it may concern:

Be it known that I, WILLIAM D. FORSYTH, a citizen of the United States, and a resident of the city of Youngstown, county of Mahoning, and State of Ohio, have invented a new and useful Improvement in Car-Truck Side Frames, of which the following is a specification.

The principal object of my invention is to provide a car truck side frame which can be easily and cheaply made and which will be light and yet strong.

The invention consists in the parts and in the arrangements and combinations of parts as will more fully appear hereinafter.

In the accompanying drawing, which forms part of this specification and in which like reference characters refer to like parts throughout the several views, Figure 1 is a plan view of the blank from which a car truck side frame embodying my invention is made; Fig. 2 is a side elevation of the finished side frame; Fig. 3 is a section on the line 3—3 of Fig. 2; Fig. 4 is an end elevation of the side frame shown in Fig. 2; and Fig. 5 is a section on the line 5—5 of Fig. 2.

A car truck side frame embodying my invention is made from two metal plates which are cut and bent by suitable apparatus and are then fastened together. The two parts of the side frame which are made from these two plates are alike and a description of one will suffice for both.

A metal plate is sheared or punched into a blank 1, which has a general triangular outline. The particular outline of the blank 1, however, may be varied according to the particular shape of the finished car truck side frame desired. In the same operation in which the blank 1 is shaped, or in a subsequent operation, a hole 2 is punched in the middle of the blank 1. The longitudinal edge portions of the blank 1 are bent along lines parallel to the edges, as indicated by the dotted lines 3, at right angles to the blank 1 to form flanges 4, and the edge por-

tions of the hole 2 are also bent along lines parallel to the edges, as indicated by the dotted lines 5, to form flanges 6. The flanges 4 and the flanges 6 project from the blank 1 in the same direction. At each end of the blank 1, spaced recesses 7 of semi-circular cross-section are made by pressing out portions of the blank in the same direction as the flanges 4 and the flanges 6 project.

After the blank 1 has been flanged and the recesses 7 made therein, it constitutes one of the two parts of the side frame. These two parts are placed back to back, with the flanges 4 projecting in opposite directions, and are securely fastened together by rivets 8 or by other suitable means. The corresponding recesses 7 of the two parts match and form holes 9, through which the bolts for fastening the journal boxes of the side frame pass. The flanges 6 align and form flanges around the opening 10 which is adapted to receive the bolster. At the bottom of the opening 10 the flanges 6 are wide and act as spring seats 11.

A car truck side frame embodying the invention above described is light and yet strong and may be easily and cheaply made. The outline of the blank 1 may be changed as desired so as to distribute the metal in the blank 1 in the finished side frame. The flanges 4 and 6 stiffen and strengthen the side frame.

Considerable change can be made in the particular construction which is herein shown and described without departing from my invention, and I do not wish to be limited to the details of such construction.

What I claim is:

1. A car truck side frame comprising two metal plates having flanges along their longitudinal edges and having aligned flanged openings therein adapted to receive a bolster, said plates being fastened together back to back with the said flanges thereon projecting in opposite directions.
2. A car truck side frame comprising two

flanged metal plates fastened together back to back and having aligned flanged openings therein adapted to receive a bolster.

3. A car truck side frame comprising two metal plates having flanges along their longitudinal edges and having aligned flanged openings therein adapted to receive a bolster, each of said plates having corresponding semicircular recesses at each end, said

plates being fastened together back to back, 10 with said flanges projecting in opposite directions.

Signed at St. Louis, Missouri, this 28th day of May, 1914.

WILLIAM D. FORSYTH.
